Primary Examiner — Randall Gholson(74) *Attorney, Agent, or Firm* — Klarquist Sparkman, LLP(57) **CLAIM**

We claim the ornamental design for a virtual holographic display device, as shown and described.

DESCRIPTION

FIG. 1 is a front perspective view of a virtual hologram display device.

FIG. 2 is a front elevation view of the virtual hologram display device of FIG. 1.

FIG. 3 is a right side elevation view of the virtual hologram display device of FIG. 1.

FIG. 4 is a left side elevation view of the virtual hologram display device of FIG. 1.

FIG. 5 is a rear elevation view of the virtual hologram display device of FIG. 1.

FIG. 6 is a top plan view of the virtual hologram display device of FIG. 1; and,

FIG. 7 is a bottom view of the virtual hologram display device of FIG. 1.
